UNITED STATES PATENT OFFICE.

GEORG PICKEL, OF CHEMNITZ, GERMANY.

SPRING BRAKE FOR WARP BEAMS OF LOOMS.

Application filed June 27, 1927, Serial No. 201,896, and in Germany July 12, 1926.

Spring-controlled brake-mechanisms for the warp-beams of looms have become known.

In comparison with these brakes of known type the brake according to this invention presents different advantages.

An adjusting screw, which is inserted into the pressure-ring of the brake-body, permits of bringing, in a simple manner and easily, all commonly used braking means as cables, bands or chains, into connection with the brake-element and to make adjustable the necessary friction between the brake-elements and disks. In this respect the different possibilities of expansion of the brake-means have been accounted for. A pressure-ring on the lower portion of the spring-sleeve or casing serves to receive the adjusting screw in a slit extension. The brake can be loaded or relieved by corresponding shifting of this pressure-ring.

The pressure-ring permits the brake to be used for several warp beams. As the pressure-ring is arranged at the lowest possible point, it has become possible to mount this brake-mechanism on looms of any system in preserving the existing brake-means. A foundation-plate fixed on the floor or directly on the loom enables to instantaneously mount or remove the brake-mechanism at the interchanging of the warp beams, simply by inserting the apparatus into or by removing the same from the stationary foundation-plate. As no tools are required the brake can be rapidly and easily mounted and removed. The possibility to work with the new brake-apparatus on warp beams situated at deep points is due to the fact that the height of the apparatus is reduced to the minimum as the lever-mechanism serving for relieving is not arranged above the apparatus but consists of a pressure-ring, shiftably mounted on the lower portion of the spring casing and adapted to be raised with the aid of a lever-system in order to slacken the adjusting screw with the brake element held by the same. The attendance is considerably facilitated as the adjusting can be effected from above, so that the brake can be applied to looms of any system.

In order to obtain special effects, for instance bindings, one frequently works in the fabric-manufacturing with several warp beams on one loom.

The new device for braking the warp beam by means of spring-pressure is ap-

plicable as well for the main beam as for the auxiliary-beams when fabrics have to be manufactured by means of several beams, the auxiliary brakes being then connected to the main-brake. These auxiliary-warp beams must be separately braked, according to the manner in which they work the material.

The spring-brake has not been used up to the present for this purpose, counter-weighted lever-brakes specially mounted in the loom having been used, which are difficult to adjust very accurately and which exert a hard shock onto the warps owing to their stability. The material is therefore put under strong stress and the uniformity of the fabric is unfavourably influenced. It is difficult to work on the warp beams as they are not easily accessible so that it is difficult for the weaver to keep the warps in order.

This invention relates mainly to a main- or single-warp-brake but as the same may be fitted also, for several beam warps, with a corresponding number of auxiliary spring-brakes, the inconveniences mentioned as regards the binding- and effect-warps are avoided. The connection is effected by inserting a bolt in the pressure-ring or, in the slit of the same, or by screwing a screw-bolt into the rear butt-strap on which screw the ring of the pull-rod having left-handed thread arranged on the lower portion of the auxiliary brake is arranged. The brake-cable is suspended to the opposite-end by means of a loop. To the springs, arranged similar to a swivel, the desired braking tension may be given by turning the springs to the left and for each warp-chain, in accordance with the fineness of the working of its warp. The relieving is effected uniformly from the handle of the main-brake by raising the same, and the loading by lowering the handle. The final pressure can be exerted with the foot as a pedal. Besides the advantages stated above another great advantage is the saving of space as the apparatus does not require special space even when several brakes are arranged. It is specially important that all the warps are free over their entire width, the rational working, only one person is required for attendance, the putting in place and removing is rapidly executed and an absolutely uniform fabric is produced. Notwithstanding the auxiliary brakes the main apparatus always operates perfectly.

Several embodiments of the invention are illustrated, by way of example, in the accompanying drawings in which:—

Fig. 1 shows in side elevation the main apparatus in the braking position.

Fig. 2 is a similar view to Fig. 1 partly in cross section and in releasing position.

Fig. 3 illustrates the auxiliary brake.

Fig. 4 shows in elevation the main-apparatus and an auxiliary brake being fixed to the rear butt-strap of the pressure-ring.

Fig. 5 shows in elevation a main apparatus with two auxiliary brakes.

Into a foundation-plate *a* fixed on the floor a base-plate *b* is inserted on which a spring-casing *c* is mounted. In this spring-casing *c* a spiral-spring *d* is located. On the top end of spring *d* rests a ball-bearing *e* designed to facilitate the putting under tension of said spring by a pressure-spindle *f* to be rotated by means of a hand-wheel. On the spring casing *c* an indicator *r* is cast in which a pinion *r*² with a pointer *r*¹ is arranged so that it can slide on a rack *r*³ fixed 25 on the spiral-spring *d* by means of a screw *r*⁴. The pointer is thus moved in accordance with the compression of the spring so that the pressure is indicated by the pointer.

A pressure-ring *g*, slidably mounted on the spring-casing *c*, has a laterally extending arm *p* in which an adjusting screw *h*² is arranged. A washer *h* having a curved top-surface permits rotating of said screw for adjusting the brake-band in the direction in which the pull is exerted, breaking of the screw being thus prevented. A hand-lever *q* serves for putting the brake-element under tension and for relieving the same. This hand-lever *q* is pivotably fixed on a bolt *v* at the top-end of the spring-casing *c* and it is connected by a link *s*, pivotable round bolts *v*¹ and *v*², with a lever *k* pivotably mounted on the other side of the spring-casing on a pivot-bolt *i*. This lever *k* is connected by a link *m*, pivotably mounted on bolts *l* and *n*, to the pressure-ring *g*.

When the hand-lever *q* is lowered, as shown in Fig. 1, the brake is applied and submitted to the pressure of the spring *d* as the spring-casing *c* intercepts the pressure of the spring between the bottom-plate *b* and the spindle-disk *r*⁵ and transmits it through the pressure-ring *g* upon the brake band.

When the lever *q* is raised, as shown in Fig. 2, the spring-pressure is not relieved but the brake pressure is relieved as the locking connection between the pressure-ring and the spring-casing has been disengaged. The warp beam can then be rotated by hand. Owing to the great lever-transmission even the highest spring-pressure can be overcome easily.

When one or several auxiliary brakes have 65 to be applied, the brake band *x* (Fig. 4) for

the warp beam is hooked over a bolt *w* or *w'* on the pressure-ring *g* (Fig. 4), or when two auxiliary brakes are to be applied the one brake-band *x* is attached to bolt *w* and the second brake-band *y* is attached to the bolt *w'* of the pressure-ring. A spring *F* (Fig. 3) is preferably inserted into the brake-band *x* or *y*. This spring *F* can be put under tension or slackened by left or right rotation, by a lower nut *G*, having left handed threads and an upper nut *H* having right handed threads. These two nuts *G*, *H* are mounted in the spring *F*. A thumb-nut *E* prevents slackening of the spring and a sleeve *I* prevents the nuts 80 dropping into the spring when the same is slack. To the end *D* of the screw *B* screwed into the nut *H* a cable, band or the like is attached which leads to the warp beam. The lower rod or wire *x* or *y* respectively are 85 attached to the bolts *w*, *w'* respectively. By raising the lever *g* the auxiliary brakes can be rapidly rendered inoperative. When the apparatus is being removed the brake cable is disconnected from the pressure-ring. 90

I claim:—

1. A spring-controlled brake for warp beams of looms, comprising in combination with the warp beam, a spring casing, a spring in said casing, means for compressing said spring by hand, a pressure-ring shiftably mounted on the lower portion of said spring casing, means connecting said pressure-ring to said warp beam and attached at the one side of said spring casing, a lever arm pivotally mounted on the other side of said spring casing, means hingedly connecting said lever arm to said pressure-ring for raising or lowering said pressure ring to make the pressure of said spring act 100 upon the brake or relieve said brake of the pressure of said spring. 95

2. A spring-controlled brake for warp beams of looms, as specified in claim 1, comprising in combination with said pressure ring and said lever arm, a transmission lever system between said lever arm and said pressure-ring for easily overcoming the spring pressure and the loading pressure of the 105 brake element upon the brake disk at the 110 loading or relieving. 115

3. A spring-controlled brake for warp beams of looms, as specified in claim 1, comprising in combination with the spring casing, a base plate of said spring casing, and a foundation plate fixed on the floor and designed to receive said base plate so that the brake apparatus can be rapidly and easily mounted in position and removed. 120

4. A spring-controlled brake for warp beams of looms, as specified in claim 1, comprising in combination with the pressure ring, bolts in said pressure ring, and auxiliary brakes to be attached to said bolts. 125

5. A spring-controlled brake for warp 130

beams of looms, as specified in claim 1, comprising in combination with the pressure-ring and the brake element attached to said pressure ring and to the warp beam, a spiral spring attached to the end of said brake element, and a threaded spindle in said spiral spring designed not only to stretch said brake element in accordance with the braking pressure to be exerted upon the braking 10 surface and to re-adjust said braking element when it has slackened but also to connect said brake element with the brake body.

6. A spring-controlled brake for warp beams of looms, as specified in claim 1, comprising in combination with the pressure-ring and the brake element attached to said pressure ring and to the warp beam, a spiral spring adapted to be adjusted like a swivel spring attached to the end of said brake element,

and a threaded spindle in said spiral spring 20 designed not only to stretch said brake element in accordance with the braking pressure to be exerted upon the braking surface and to re-adjust said braking element when it has slackened but also to connect said 25 brake element with the brake body.

7. A spring-controlled brake for warp beams of looms, as specified in claim 1, comprising in combination with the spring casing and the spring in said casing, a box on 30 said casing, a pinion in said box, a pointer made in one piece with said pinion, a rack in said spring casing and meshing with said pinion, and a screw connecting said rack to said spring so that said pointer indicates 35 the pressure of said spring.

In testimony whereof I affix my signature.
GEORG PICKEL.
